UNITED STATES PATENT OFFICE.

JACOB C. GROBLE, OF ANDERSON, INDIANA.

GAS-PRESSURE REGULATOR.

1,283,502.

Specification of Letters Patent. Patented Nov. 5, 1918.

Application filed July 16, 1918. Serial No. 245,187.

To all whom it may concern:

Be it known that I, JACOB C. GROBLE, a citizen of the United States, and a resident of Anderson, county of Madison, and State of Indiana, have invented a certain new and useful Gas-Pressure Regulator; and I do hereby declare that the following is a full, clear, and exact description thereof, reference being had to the accompanying 10 drawings, in which like figures refer to like parts.

This invention relates to gas pressure regulators particularly of the automatic type, and is an improvement over my former application, Serial No. 219,209, filed February 15, 1918.

The prime feature of the invention is the provision of means for quickly attaching or removing the valve from its supporting 20 means. A further feature of the invention is the provision of means upon the valve for frictional engagement with the valve supporting lever for holding the valve in engagement with its support, and at the same 25 time permit vertical adjustment of the valve. A further feature of the invention is in so constructing the valve attaching means that the valve will be held against undue lateral swinging or rotating movement.

30 In the accompanying drawings which are made a part of this application, Figure 1 is a side elevation, partly in section, of a gas regulator showing the manner of attaching the valve with the valve supporting lever. 35 Fig. 2 is a sectional view as seen on line 2—2, Fig. 1. Fig. 3 is an enlarged detail sectional view as seen on line 3—3, Fig. 1. Fig. 4 is an enlarged central sectional view of a valve showing a modified means for attaching the valve to its hanger.

40 Referring to the drawings, 1 indicates a trap frame of a gas pressure regulator which is of the usual form, and preferably formed of two sections, the lower section 45 having a depression 2 therein which forms a laterally extending channel 3, one end of which terminates in a sleeve 4, the ends of the sleeve being internally threaded for engagement with a pipe line (not shown). 50 Immediately above the lower threaded portion of the sleeve is formed a bridge 5 into which is threaded a thimble 6, the upper end of which terminates in a seat 7 for the reception of a valve 8. This valve is em-

ployed for regulating or stopping the flow 55 of gas through the thimble.

The valve 8 is suspended from one end 9 of a lever 10, said lever being pivoted in the channel 3, the pivoting point 11 being in close proximity to the end 9 of the lever. The inner end of the lever 10 is pivotally 60 attached to the well known form of dia- phragm 12, through the medium of which the lever 10 is rocked on its pivot to raise or lower the valve 8 attached thereto.

65 The end 9 is of considerable less depth than the remainder of the lever 10 so as to form a vertical rib 14, in the opposite faces of which are formed vertical grooves 15. Extending through the flattened end 9 is 70 an adjustable support 16, that portion of the support extending below the end 9, having a peripheral channel 17 therein for engagement with a hanger 18 of the valve 8 so as to suspend the valve from the support. The 75 hanger 18 comprises a body portion 19 which is shown in the various figures as resting upon the top of the valve 8, and said body portion may be brazed, spotwelded or otherwise secured to the top of the valve, 80 or as shown in Fig. 4, a stud 20 may be formed at the axial center of the valve 8, which stud projects through an opening 21 in the body portion 19 and the upper end of the stud then upset or riveted. When this 85 form of means is employed for attaching the valve to the hanger, the stud will serve as a centering point for the hanger.

One end of the body portion 19 is ex- 90 tended beyond the peripheral edge of the valve 8 and bifurcated to form spring fin- gers 22, which fingers are given a half turn so as to present the flat faces thereof at right angles to the flat face of the body portion carrying the fingers. The spring fin- gers 22 are each provided with an inwardly 95 bowed portion 23 adjacent to the free end of the finger, which bowed portions are adapt- ed to snap into the grooves 15 of the rib 14, when the valve is properly positioned over 100 the seat, the free ends of the spring fingers being flared outwardly so that they will readily ride over the edges of the rib 14. The opposite end of the body portion 19 is 105 curved upwardly and the free end 24 thereof disposed over the body portion 19, said free end 24 having a longitudinally extending slot 25 therein for engagement with the

channel 17 of the support 16, the slot 25 being of sufficient width to snugly receive the reduced portion of the support. Instead of forming the hanger construction separate 5 from the valve structure and then attaching the same thereto, the hanger and valve may be formed integral as may be found expedient.

One wall of the sleeve 4 is provided with 10 a removable plate 26 whereby a ready access may be had to the interior of the sleeve and through the medium of which the valve 8 may be removed from or engaged with the end of the lever 10. In introducing the 15 valve into position, the support 16 having previously been properly adjusted in the end of the lever 10, the valve is moved inwardly in a straight line through the opening in the side of the sleeve 4, and the groove 20 portion of the support engaged with the slot in the end 24 of the hanger, and simultaneously with this operation, in view of the fact that the fingers 22 are extending forwardly of the valve, the flared ends of the 25 fingers will contact with the rib 14 and ride over the opposite faces thereof, and when the support has reached the inner end of the slot 25, the bowed portions 23 of the fingers will snap into the grooves 15 of the 30 rib, thereby frictionally holding the valve in supported position. When the valve is to be removed, a straight outward pull is given to the valve, which will overcome the spring tension of the fingers 22 and permit the end 24 of the hanger to release from its support, the action of disengaging and 35 replacing the valve being very easily and quickly accomplished. Furthermore, it will be seen that by disposing the grooves 15 vertically, the valve can be adjusted vertically with respect to its seat, as occasion 40 may require, without affecting the gripping action of the fingers upon the rib. It will likewise be seen that in view of the fact 45 that a finger passes on each side of the rib 14, and the said rib is stationary, the fingers will serve to hold the valve against rotating or undue laterally swinging movement.

50 By attaching the valve to the lever in the manner herein shown, a defective valve can be readily removed and repaired or a new one inserted in its place without necessitating the cutting off of the supply of gas an 55 unreasonable length of time, which is necessary in repairing valves which are permanently secured to the operating lever, as it is necessary to remove parts of the regulator in that instance and return the same to the

factory in order to repair the same, while 60 with applicant's device, but a very few minutes are required to renew the valve and in fact the gas is only cut off the length of time that it takes to remove the plate 26 and return the same to position. 65

The invention claimed is:

1. In a gas pressure regulator, the combination with a lever, of a valve, means to support the valve from the lever and means carried by the valve for frictional 70 engagement with parts of the lever to hold the valve on its support.

2. In a gas pressure regulator, the combination with a lever having a rib thereon and a valve support carried by the lever, 75 of a valve means to removably attach the valve to its support, and means on the valve adapted to frictionally engage said rib to hold the valve in position on its support.

3. In a gas pressure regulator, the combination with a lever, and a valve support carried thereby, of a valve, a hanger on the valve adapted to engage said support and suspend the valve therefrom, and means carried by the valve for frictionally engag- 80 85 ing parts of the lever for holding the valve in position.

4. In a gas pressure regulator, the combination with a lever, and a valve support adjustably attached thereto, of a valve, 90 means on the valve for engagement with said support, and spring fingers carried by the valve adapted to engage parts of the lever and hold the valve in position on its support and against rotation. 95

5. In a gas pressure regulator, the combination with a lever, and an adjustable valve support carried thereby, said support having a channel, of a valve, a hanger attached to the valve and having a slot for 100 engagement with the channel of the support, and means for frictionally engaging the valve with parts of the lever, whereby said valve may be quickly engaged with or disengaged from the lever. 105

6. In a gas pressure regulator, the combination with a lever, an adjustable support carried thereby, and a rib on the lever having vertical grooves, of a valve, a pair of spring fingers carried by the valve 110 adapted to be engaged with the grooves of said rib to hold the valve against rotation, and means on the valve adapted to engage said support and suspend the valve.

In witness whereof, I have hereunto af- 115 fixed my signature.

JACOB C. GROBLE.
